UNITED STATES PATENT OFFICE.

WALTER H. NOURSE, OF PORTLAND, OREGON, ASSIGNOR TO ELECTRIC STEEL FOUNDRY,
OF PORTLAND, OREGON, A CORPORATION OF OREGON.

METHOD OF CASTING GEARS OR THE LIKE OF MANGANESE STEEL WITH SOFT-IRON
CENTERS.

Application filed October 7, 1926. Serial No. 140,089.

My invention relates to casting gears, pinions, and other machine elements cast of hard metal, such as manganese steel, and whose bore must be fitted for firmly mounting on a shaft. Since manganese steel is not readily machined by any other process than grinding, the casting is provided with a center of machinable metal, such as soft iron.

This construction is particularly required, 10 for example, in gears and pinions intended for repairs of geared locomotives; for, with the majority of repairs on these locomotives, it is necessary to bore each gear or pinion to suit the diameter of the line shaft. When 15 the locomotive is in service, the diameters of the line shafts are unknown at the shop where the replacement gear or pinion is supplied; and therefore, it is the custom to order the pinion or gear "rough-bored," ready to 20 "finish-bore" to suit the diameters of the line shaft at the time the locomotive is laid up for repairs. In the method of casting heretofore generally followed, the soft iron center was in the form of a continuous ring or 25 bushing, constituting a hub or boss-like section. The difficulty with such method was the solid center tended to set up excessive strains in the hub section during the casting operation, which resulted in cracking the 30 hub, and rendering the center loose in the casting.

Such cracking of the hub or boss-section is due to unequal expansion and shrinkage, during the casting operation, between the soft 35 iron center and the mass of manganese steel cast about it.

According to my observation, manganese steel has a defined elastic limit which may not be exceeded with impunity. And experiments with manganese steel have established the fact that this metal has a co-efficient 40 expansion of approximately .00001 inches per inch per degree Fahrenheit, while soft iron, according to Kent's Mechanical Engineers' Hand Book, has a co-efficient of expansion of approximately .0000065 inches per inch per degree Fahrenheit.

Furthermore, the soft iron center has to have sufficient thickness to permit machining 50 as required to render the bore of proper size. The soft iron center heats up relatively slowly during the casting operation, and after the manganese steel is cast, the center

continues to expand while the manganese steel is cooling. 55

At this instance, the manganese steel is extremely tender, and the unequal expansion of the two metals tends to burst the tender casting, thus causing the gear, or other machine element to be unfit for further service. 60 The strains imposed by unequal shrinkage of the two metals under the said old method of casting is apt to be particularly severe, because after the gear or pinion is permitted to cool, it is again heated to about 1800° 65 Fahrenheit, and then plunged in cold water, to effect the so-called heat treatment for rendering the manganese steel ductile.

I discovered that said tendency of cracking the hub section of the pinion is overcome 70 by making the inserted center in segments, instead of in one continuous piece; and making the segments of such circumferential measurement as to leave a substantial space 75 between their adjacent sides. When the body of the gear is then cast about the said segments, integral tongues of the cast manganese-steel will flow into, and form in said spaces between the segments. The spacing must be such as to give the said integral 80 tongues of manganese steel sufficient mass in cross-sectional area to compensate for the difference in shrinkage in the cooling of said two metals; in that way avoiding the setting 85 up of the excessive strains which would tend to crack the hub section of the gear or pinion.

Furthermore, the arrangement of the parts must be such that the segments will be firmly held in the cast body of the manganese steel against moving longitudinally in the bore, 90 or into the bore of the gear. This is conveniently accomplished by firmly wedging the segments between said integral tongues.

The manner of carrying my invention into practise is illustrated in my accompanying 95 drawings with respect to the casting of a pinion.

In the drawings:

Fig. 1 shows a front elevation of a pinion embodying my invention, and mounted on its 100 shaft which is shown in section, the central portion of the pinion is also shown in section, in order to disclose the arrangement of the soft metal segments, their spacing apart, and the integral tongues of the cast manganese 105 steel formed between them; and

Fig. 2 shows a section taken on the line 2—2 of Fig. 1 looking down on the lower half of the pinion, as indicated by the arrows.

Fig. 3 shows the particular form of central core employed by me in making my casting; and

Fig. 4 shows the machinable segments secured to such central core with the latter inserted, and the core box ready for making the casting.

My invention as above mentioned is to be applied to gears, pinions, and other machine elements cast of hard metal, such as manganese steel, and provided with a machinable softer metal center.

My center insert consists of a plurality of circular segments as *a*, *b*, and *c* arranged about the center of the pinion, or gear, to be cast, and supported in place, during the casting operation, by a proper core prepared for that purpose. The lateral sides of the segments must be spaced a substantial distance apart, as illustrated by Fig. 1.

The segments *a* is formed with a key-bass *d*. The body *e* of the pinion or gear is then cast about said segments, thus causing integral tongues of the cast manganese steel to flow in between the sides of the spaced segments as indicated at *f*. The sides of the segments must be spaced such distance apart that the integral tongues *f* will have sufficient mass in cross-section to compensate for the difference in shrinkage at the time of the cooling of said two metals.

I have found the practical limits of these spaces to be from approximately 15° to 20° of arc for gears and pinions having a bore of three inches to four inches in diameter.

The core used in making the casting must be adapted to so arrange the parts that the faces *g* of the segments exposed to the core of the pinion will project beyond the corresponding faces of the tongues *f* a sufficient distance to provide metal for machining the center as may be required.

In order to provide for locking or wedging of segments firmly between their integral tongues, the sides of the segments are preferably formed to lines radial with the center of the pinion or gear; thus forming these segments into key-like or wedge-like sections, larger at their outer periphery than at their inner periphery, and thereby securely holding the segments from moving into the bore of the pinion.

I preferably make the center of my gear or pinion of three parts or segments,—*a*, *b*, *c*—so as to get a three-point bearing effect. But each of these parts may be composed of two or more units, as may be required where the diameter of the pinion or gear is considerable.

In either case, the three segments of the centers should be disposed approximately on

centers of 120° as above stated; thus with the spacings of the segments about 15 to 20 degrees apart—for pinions having a bore of three to four inches diameter. Any lesser spacing is apt to cause the severe strains in cooling, which is the purpose of my invention to avoid.

My experience has demonstrated that a relatively greater shrinkage takes place in the cross-section of the tongues *f* on the casting entering between the segments *a*, *b*, and *c* than in the body of the metal cast about the segments, similarly to the shrinkage of the teeth or cogs in the casting of manganese steel gears and pinions, the teeth of which have to be cast of such thickness as to compensate for their relatively greater shrinkage in cross-section than the shrinkage in the body of the gear or pinion.

That is to say there is a definite relation between the cross-sectional areas of the segments and that of the casting, otherwise the chilling effect of the segments upon the hot metal cast about it will tend to set up undue stresses and strains during the casting operation, tending to crack the hub section of the casting.

In making my casting, I first make a cylindrical core *i* formed with peripheral recesses as *j*, shown by Fig. 3, and insert the same in the center of the core box *k*. On such central core in its said recesses are secured the segments *a*, *b*, and *c*, by means of a wire *l*, and the central core with the segments secured in place is then inserted in the core bore whereupon the latter is ready for the casting. The peripheral projections *m* of the core extending between the said segments serve to produce the tongue *f* between the segments and hold back the flow of the hard metal to a circle of greater diameter than that of the circle touched by said segments, thus causing the latter to project beyond the hard metal body into the center of the casting, and thereby providing ample machinable metal in the eye of the pinion, or similar machine element.

I claim:

The method of casting a pinion and similar machine element of hard metal with a machinable center, which consists in mounting a plurality of soft metal segments in spaced relation on a core, and then casting the harder metal about said core, whereby tongues of the hard metal will flow into and form between the said segments and lock the same in place, the flow of said tongues being confined to a circle of greater diameter than that of the circle touched by the said soft metal segments, and the latter segments projecting beyond the hard metal body in the center, and the spacings between the segments being proportioned substantially as described.

WALTER H. NOURSE.
